(57) **CLAIM**

The ornamental design for a hose clamp guard, as shown and described.

DESCRIPTION

FIG. 1 is a top perspective view of a hose clamp guard at a reduced scale showing my new design;

FIG. 2 is another perspective view thereof;

FIG. 3 is a front elevational view thereof;

FIG. 4 is a top plan view thereof, the bottom plan view being identical;

FIG. 5 is a rear elevational view thereof; and,

FIG. 6 is a right side elevational view thereof, the left side elevational view being identical.

The broken line showing the hose clamp in the figures is for illustrative purposes only and forms no part of the claimed design.
